UNITED STATES PATENT OFFICE.

EDWARD S. STIMPSON, OF HOPEDALE, MASSACHUSETTS, ASSIGNOR TO DRAPER COMPANY, OF HOPEDALE, MASSACHUSETTS, A CORPORATION OF MAINE.

THREAD-PARTER AND THREAD-CLAMP.

1,198,787.

Specification of Letters Patent. Patented Sept. 19, 1916.

Application filed April 30, 1915. Serial No. 25,036.

To all whom it may concern:

Be it known that I, EDWARD S. STIMPSON, a citizen of the United States, residing at Hopedale, county of Worcester and State 5 of Massachusetts, have invented an Improvement in Thread-Parters and Thread-Clamps, of which the following description, in connection with the accompanying drawings, is a specification, like letters on the 10 drawings representing like parts.

The present invention relates to thread parting and clamping means for looms.

In filling replenishing looms of the "feeler" type, wherein mechanism is employed for introducing a fresh supply of filling to a running shuttle or substituting a filled shuttle for the one in use, the end of the old filling extends from the cloth to the shuttle containing the carrier or bobbin 15 to be abandoned, and it is desirable that this end of filling be removed from the loom so that it shall not be carried into the shed. Means have been provided to this end, among which may be mentioned that exploited in the patent to Northrop and 20 Stimpson, No. 641,792, January 23, 1900, and that in the patent to Draper, No. 683,423, September 24, 1901. In the former, the thread parter has associated therewith 25 a thread clamp and both are moved toward the lay upon call for filling replenishment to part and clamp the filling and then move the filling end toward the front of the loom for the action of the temple thread parter. The loose end of filling is retained by the 30 clamp until another call for replenishment, whereupon, as the parter and clamp again move toward the lay, they are opened to repeat the operation thus freeing the old piece 35 of filling. In the Draper patent referred to, and others, such as Nos. 677,096; 677,097; 677,098; dated June 25, 1901, the thread parter and clamp have had associated with them a thread catcher to engage the filling 40 end and retain it after it has been released by the clamp.

In the present invention, the thread parter and thread clamp may have the characteristic movement from the front of the loom toward the lay to clamp and part the filling upon call for filling replenishment, and then back again to initial position as in the 50 patents noted, and in connection therewith, the invention contemplates that after return 55 to initial position at the front of the loom,

the filling end will be held by the clamp a sufficient length of time to insure being parted by the temple thread parter and then released while still in such front position, so that danger of the piece of detached filling being caught and carried into the shed 60 is avoided.

Another important feature of the present invention consists in providing simple but effective means for opening the thread parter and clamp while they are in initial or front position.

The relation of the thread parter and thread clamp and the control of the latter by the former, as well as various other important features of the invention, will be made clear from the following description and accompanying drawings of a good form of means for carrying the invention into practical effect, it being understood that in 70 its true scope the invention is defined by the claims.

In the drawings:—Figure 1 is a side elevation of a thread parter and thread clamp embodying the present invention, only so much of the lay and front of the loom being illustrated as to make generally clear the relation of parts; Fig. 2 is a plan view showing the thread parter and thread clamp in their associated relation, the carrying arm being broken away; Fig. 3 shows the thread parter and thread clamp closed upon the filling thread by the lay as the latter beats up; Fig. 4 is an end view of the thread parter and thread clamp looking in the direction 75 of the arrow, Fig. 1, and showing the thread parter at or about the time it is parting the filling and the clamp in holding position; and Fig. 5 is a section on the line 5—5, Fig. 3.

The loom frame may be of any appropriate character and construction to support the operating parts, only a portion of one of the uprights 1 being herein illustrated for the purpose of clearness. Said upright 100 1 may be surmounted by the usual breast beam, but as these matters are all well understood by those skilled in the art, illustration is not necessary.

Adjustably mounted upon the upright 105 1 is the bracket 2 having the rearwardly-projecting arm 3 carrying a stud 4 with respect to which the shuttle feeler arm or carrier 5 is pivotally mounted. This shuttle feeler arm or carrier 5 together with its projecting 110

stud 6 and the pin 7 may all be substantially as fully set forth and described in Patent No. 683,423, hereinbefore referred to. As described in the said patent, the shuttle 5 feeler arm or carrier 5 is movable from an inoperative position at the front of the loom to an operative position nearer the back of the loom upon call for filling replenishment in order to position the shuttle feeler and 10 thread parter and thread clamp for engagement with the filling extending between the cloth selvage and shuttle. Any appropriate means may be employed for thus giving to the shuttle feeler arm or carrier 5 its movement to and from operative position, and an appropriate form of means to this end is fully described in the patent hereinbefore mentioned, and since such means forms no essential part of the present invention, and 15 is well understood by those skilled in the art, further illustration and description herein is unnecessary.

The rear end portion of the shuttle feeler arm or carrier 5 is provided with a shoulder 25 8 and a thread rest 9, the front and side portions 10 and 11 of the thread rest 9 being beveled or cut away, as indicated in Fig. 2, in order that the filling thread leading from the cloth selvage to the shuttle may readily 30 position itself upon the rest 9 and be guided thereto by the inclined portions 10 and 11.

The present invention contemplates that upon call for filling replenishment, the shuttle feeler arm or carrier 5 shall be moved 35 from its front or inoperative position to its rear or operative position to act upon the filling thread, and that there shall be provided a thread parter to part the filling and a thread clamp to clamp the end of the filling leading from the cloth selvage so that upon the return of the shuttle feeler arm or carrier 5 to its front or inoperative position, the end of the filling thread leading from the cloth selvage shall be carried forward 40 and held in position for the action of the usual temple thread parter.

In the present form of the invention, the thread parter comprises a fixed blade 12 secured to the end portion of the shuttle feeler 50 arm or carrier 5, substantially as indicated in Figs. 2 and 5, and a relatively movable member 13 which may be appropriately supported by the shuttle feeler arm or carrier for relative movement with respect to the 55 companion member 12 of the thread parter to part the filling.

In the present illustrated form of the thread parter, the member 13 is formed as a pivoted member pivotally supported by a 60 bolt 14 which passes through the end of the shuttle feeler arm or carrier 5, then through the pivoted member 13 of the parter and finally through an overlying plate 15 between which and the member 12 of the 65 parter, the pivoted member 13 may rock.

The bolt 14 is provided with a shoulder which bears exteriorly upon a spring washer 16 resting against the plate 15, the construction being such that the spring washer 16 acting through the plate 15 upon the movable member of the thread parter retards too free movement of said movable member. In order further to establish the associated relation of the shuttle feeler arm or carrier and the members of the thread parter and 75 the overlying plate 15, another bolt or pin 17 may be passed through the parts and into the end of the shuttle feeler arm or carrier, substantially as indicated in Fig. 2.

It is desirable that the movable member 80 of the thread parter shall have a limited movement, and to this end it is provided with an opening 18 through which the pin 17 is passed, and which serves as a limiting stop for the opening and closing movements 85 of the movable thread parter member 13.

The parts thus far described may be of any appropriate character suitable for parting the filling, but preferably one of the members of the thread parter, the member 90 12 in the illustrated form of the invention, is made laterally yieldable so that as the two members of the parter act upon the filling thread, they insure a shearing cut.

The movable member 13 of the thread 95 parter has a down-turned tail portion 19 which is adapted to be engaged by a bunter 20 on the lay 21 as the latter beats up, when the thread parter is in its rear or operative position, the construction being such that the thread having been introduced between the members of the thread parter, the relative movement of the members of the parter under the conditions noted, will cause the filling thread to be parted between the cloth 100 selvage and shuttle. When the lay beats up and the parter is in operative position, the inclines 10 and 11 guide the filling thread to the rest 9 upon which it is supported during the action of the parter. The character 105 of thread parter described has been found well adapted for its purpose, but the invention is not necessarily limited thereto and includes other forms of thread parters which may be associated with features of the 110 present invention.

Mounted upon the tail end portion 19 of the member 13 of the thread parter, is a weight 22 which, when the thread parter has returned to inoperative position, serves 115 120 to overcome the retarding influence of the spring washer 16 upon the movable member of the parter, and, under the vibrations of the loom, to open or separate the members of the thread parter.

The plate 15 has formed as a part thereof, or secured thereto, a lug 23 provided with a groove 24 adapted to be engaged by a thread clamp 25. The front end portion of the lug 23 has an inclined wall 26 leading 125 130

to the upper surface thereof, substantially as indicated in Fig. 3, and a back wall 27 provided with a slot 28 by which the movements of the thread clamp, to be presently described, may be guided.

The present invention contemplates that after the thread parter has parted the filling between the cloth and shuttle, and the thread clamp has engaged the end of the

10 filling leading from the cloth, and the thread parter and thread clamp have returned to initial position at the front of the loom, the clamp will continue to hold the end of the filling leading from the cloth

15 until or about the time the temple thread cutter parts the thread at the cloth selvage, and that then the thread parter and thread clamp shall be opened to again perform their parting and clamping functions on a

20 subsequent call for filling replenishment. To this end, the weight 22 connected to the tail end portion of the movable member of the thread parter, is made sufficiently heavy to move the movable member of the thread

25 parter into open position under the vibrating influence of the loom; and to effect release of the filling end leading from the cloth, the thread clamp is also under operative influence of said weight.

30 As one means to thus operate the thread clamp, and cause it to release the end of the filling leading to the cloth selvage at the front of the loom, the present invention contemplates a connection between the

35 weight and the thread clamp, so that as the said weight opens the thread parter it may act also to unclamp the thread.

In the present form of the invention, the thread clamp is shown as formed of spring

40 wire having a coil portion 29 wound about the outer portion of the bolt 14, between the head 30 thereof and the spring washer 16. From the coil portion 29 the clamping member leads forward, or to the left, in

45 Figs. 1, 2 and 3, and passes through the slotted portion 28 of the back wall 27 of the lug 23, its outer end being turned upwardly as indicated in Fig. 3, in order to direct the filling thread between the end

50 portion of the clamp and the groove or seat 24. The rearwardly-extending portion 31 of the thread parter engages a stud 32 extending laterally from the weight 22, the construction being such that when the thread

55 parter is closed to perform its parting function by engagement of the bunter 20 with the tail portion of the movable member of the parter, the weight 22 will be lifted, and the thread parter be turned about the bolt

60 14 as an axis to clamp the thread between the end of the parter and the grooved lug 23, substantially as indicated in Fig. 5, the parts at such time being in their operative or rear position with respect to the lay.

65 When the shuttle feeler arm or carrier 5 is

then moved to its front or inoperative position, the members of the parter remain closed and the clamp remains seated upon the filling leading from the cloth. The weight 22 is such, however, that acting upon the tail portion of the parter and under the vibrations of the loom, the movable member of the parter will be turned about its pivotal axis to open or separate the members of the parter, and, since the thread clamp is connected to the movable member of the parter through the weight 22, it likewise partakes of such movement and, after the filling has been parted at the cloth selvage, unclamps the end, thus permitting it to drop clear of the operating parts of the loom.

It is found convenient and preferable to have the thread clamp move into engagement with the filling thread in advance of the thread parter and to hold the filling firmly against the lug 23 as the parter performs its parting function. This is effected in the present form of the invention by positioning the clamping portion of the clamp somewhat in advance of the parting edge of the parter so that as the clamp and parter move to closed position, the clamp will first engage the thread and thereafter the parter will part it. In the character of clamp herein described, as the present embodiment of the invention, this disposition of the thread parter and clamp serves to augment the opening action of the weight 22 when the parts are in inoperative position at the front of the loom, because the rear end portion 31 of the wire clamp acts with spring force to assist in the downward movement of the weight 22 under the influence of the loom vibration.

From the construction described as a convenient form of the present invention, it will be noted that when the thread parter and thread clamp have been moved to operative position toward the rear of the loom, and have performed their thread clamping and thread parting functions, and then return to inoperative position toward the front of the loom, the weight is sufficient to move the movable member of the parter and then to release the end of the filling thread from the clamp without the interposition of any exterior means. Thus, a simple, yet effective and reliable means is provided to part the filling between the cloth and the shuttle, to carry it to the front of the loom, and then release it.

What is claimed is:—

1. In a loom, a thread parter and a thread clamp movable toward the lay into operative position to part and clamp the filling between the cloth and shuttle, and gravity means acting to open the parter and clamp after the parter and clamp have been returned to inoperative position at the front of the loom.

2. In a loom, a thread parter comprising relatively movable members, means for retarding relative movement of said members, and means acting continuously upon the 5 parter and clamp to permit them to remain closed until they are returned to front position and then acting to open them and release the filling end at the front of the loom.
3. In a filling replenishing loom, a thread 10 parter comprising relatively movable members, means for retarding relative movement of said members, and a weight for relatively separating said members after they have been returned to front position.
4. In a filling replenishing loom, a thread 15 parter comprising relatively movable members, means for retarding too free relative movement of said members, and causing them to remain closed after a parting and 20 clamping action, and a weight connected to one of said members for relatively separating said members to free the filling end after the parter and clamp have returned to front position.
5. In a filling replenishing loom, a thread 25 parter comprising relatively movable members, means for retarding relative movement of said members, a weight for relatively separating said members, and an independent 30 thread clamp operated by said weight to unclamp the thread after the thread has been carried to the front of the loom.
6. In a filling replenishing loom, the combination of a thread parter comprising relatively movable members, an independent 35 thread clamp, and a weight connected to both the thread parter and thread clamp for relatively separating the members of the thread parter and opening the clamp.
7. In a filling replenishing loom, the combination of a thread parter and thread 40 clamp movable from an inoperative position at the front of the loom to an operative position nearer the rear of the loom, means for closing the parter and clamp when in operative position, and a weight for opening the parter and clamp after they have been returned to inoperative position at the front of the loom.
8. In a filling replenishing loom, the combination of a thread parter and a thread 45 clamp, an arm for moving said parter and clamp to and from operative position, and thread parter and clamp opening means
- carried wholly by said arm and acting continuously on the parter and clamp to effect opening movement thereof by the loom vibration after they have been closed to part and clamp the thread and returned to front or inoperative position. 55
9. In a filling replenishing loom, a thread parter including a pivotally mounted member having a thread parting portion at one side of the pivotal mounting and a tail portion at the opposite side thereof, and a 60 weight connected to the tail portion for turning said member on its pivotal mounting to an open position under the vibrating influence of the loom after the parter has returned to the front of the loom. 65
10. In a filling replenishing loom, a thread parter including a pivotally mounted member having a thread parting portion at one side of the pivotal mounting and a tail portion at the opposite side thereof, a weight 70 connected to the tail portion for turning said member on its pivotal mounting to an open position under the vibrating influence of the loom, and a thread clamp having a portion connected to said weight for opening the clamp. 75
11. In a filling replenishing loom, a thread parter including a pivoted member, a pivotally mounted wire thread clamp and a weight for moving the said pivoted member 80 and wire clamp to open position. 85
12. In a device of the character described, the combination of a thread parter and thread clamp, and a weight connected to the clamp to cause the clamp to open and free 90 the thread after the clamp has returned to front position in the loom. 95
13. In a filling replenishing loom, a thread parter comprising relatively movable members to engage and part the thread, and means acting continuously upon the parter to permit the members to remain closed after a thread parting operation until they have been returned to front position and then acting to open them at the front position. 100

In testimony whereof, I have signed my name to this specification, in the presence of two subscribing witnesses.
